ROVING FRAME

Application filed December 21, 1932, Serial No. 648,298, and in Great Britain January 14, 1932.

This invention relates to improvements in roving frames of the type used for jute in which the bobbins are positively driven by gearing and has for its object to provide an improved doffing arrangement for such frames.

As is understood, in a jute roving frame the flyers are arranged in a double row including a front row and a rear row.

10 A roving frame constructed in accordance with the present invention is equipped with flyers suspended from driven spindles journalled in a fixed overhead rail and with a bobbin lifter rail adapted to be tilted about the axis of a bobbin-driving shaft extending longitudinally of the bobbin lifter rail intermediate the rows of bobbin-carrying spindles.

As is understood, in operative position the 20 bobbin spindles are upright and aligned with the axes of rotation of the relative flyers.

The arrangement is such that, when the flyers are stopped in a given position, both 25 rows of bobbins can be swung through the flyers to a forwardly inclined position in which the full bobbins can be readily doffed and replaced by empty bobbins.

Suitable power-driven or hand-driven 30 inching apparatus may be provided for bringing the flyers to the correct position to permit passage of the bobbins in case the flyers should fail to stop in the correct position; or the correct positioning of the flyers 35 may be effected by direct manipulation of one of the flyers, it being understood that, when one flyer is turned, all the other flyers are turned.

The gearing for driving the flyers may 40 comprise spiral or bevel gears. The bobbins are differentially gear-controlled as in the usual jute roving frame.

According to a modified arrangement in which the bobbin spindles of each row are 45 staggered relatively to the bobbin spindles of the other row, to enable the bobbins of the rear row to clear the front flyers when doffing, the bobbin lifter rail, in addition to being tiltable about the axis of the bobbin driving shaft, may be displaced axially of

said shaft. The timing of the forward swing of the bobbin spindles may be controlled by a cam or the like which ensures that the bobbins of the rear row clear the front flyer legs.

The invention is illustrated in the accompanying drawings in which Fig. 1 is a transverse vertical section, Fig. 2 a fragmentary elevation at 180° to Fig. 1 drawn to a larger scale, and Fig. 3 a fragmentary plan view; Fig. 4 is a fragmentary plan view showing a modification.

The roving frame shown in Figs. 1-3 is equipped with a front row of flyers 1 and with a rear row of flyers 2, arranged in non-staggered relation, and suspended from front and rear rows of spindles 3, 4, respectively, journalled in a fixed overhead rail 5. 6 denotes the bobbin lifter rail which is adapted to be tilted about the axis of a horizontal bobbin driving shaft 7 between normal or operative position as shown in full lines in Fig. 1 in which front and rear rows of bobbin spindles 8, 9 upstanding from the rail 6 are disposed in coaxial relation, respectively, with the flyer spindles 3, 4 and the position shown in dotted lines in Fig. 1 and in full lines in Fig. 2 in which the bobbin spindles 8, 9 are inclined forwardly clear of the flyers 1, 2 to permit doffing and reloading.

For effecting tilting movements of the bobbin lifter rail 6 there is attached to said rail, concentric with the shaft 7, a toothed segment 10 (Fig. 2) meshing with a worm 11 on a shaft 12 journalled in the lifter bracket 6 and rotatable by means of a hand-wheel 13.

14, 15 denotes the bobbins which are positively driven from the shaft 7 through gearing of known form carried by the rail 6 as shown best in Figs. 1 and 3, the bobbins being impaled on the spindles 8, 9 which are carried by bobbin-drivers 16 presenting driving pegs 17 engageable by sockets 18 in 95 the bases of the bobbins.

The flyer spindles 3, 4 are journalled in ball bearings 19, 20 and each flyer spindle carries a gear pinion 21 meshing with a gear pinion 22 on a flyer driving shaft 23. 100

When the frame is stopped prior to doffing, in case the arrested position of the flyers is such that the flyers obstruct tilting movement of the bobbins, the flyers must be 5 rotated to clear the bobbins; the main drive to the shaft 23 being disconnected, the operative may correct the position of all of the flyers simultaneously by simple manual rotation of any one flyer. If the shaft 23 is 10 belt driven, the drive may be disconnected by a simple-belt-shift operation.

In correcting the positions of the flyers prior to doffing, the flyers are preferably rotated reversely so that sufficient slack rove 15 is withdrawn from the bobbins to allow the bobbins to be tilted forwardly into doffing position without straining the rove. When the bobbins are in doffing position, each rove 20 yarn is broken in the usual manner before the relative bobbin is doffed.

As will readily be understood, the construction according to the invention permits the drawing roller indicated at 24 to be so located as to make the rove ends 25, 26 leading, respectively, to the front and rear flyers, substantially equal. The importance of this 25 feature will be appreciated by those skilled in the art.

While we have shown the bobbin spindles 30 as being rotatable, it is to be understood that the bobbin spindles 8, 9 may be non-rotatable and act as carriers for the bobbins and the bobbin-drivers.

In the modification shown in Fig. 4 the 35 bobbin spindles of each row are staggered relatively to the bobbin spindles of the other row, and, to enable the bobbins of the rear row to clear the front flyer legs when doffing, the bobbin lifter rail 6, in addition to being 40 tiltable about the axis of the shaft 7, is adapted to be displaced axially of the shaft 7 whereby to permit the bobbins of the rear row to be swung forwardly through the legs 45 of the front flyers. To this end, there is fixed to the lifter rail 6 an upstanding follower pin 27 adapted, when the rail 6 is displaced endwise, to track a cam slot 28 presented by a bracket 29 fixed to the lifter bracket 6^a and overhanging the rail 6, the cam slot 28 being oblique to the axis of the shaft 7 so that endwise movement of the rail 6 is accompanied by tilting movement 50 of said rail 6. The rail 6 is provided with a segmental rack 30 concentric with the shaft 7 and engaged by a worm 31 operable by means of a handwheel 32 and journalled in a bracket 33 carried by the lifter bracket 6^a. As will readily be understood, the construction is such that endwise movement imparted to the rail 6 by rotation of the handwheel 32 is accompanied by tilting movement 55 of the rail 6 by virtue of the circumstance that the pin 27 is constrained to track the cam slot 28.

The bobbins of both rows rotate in the same direction.

What we claim is:—

1. A roving frame, comprising, in combination, a fixed overhead rail, two rows of 70 driven spindles journalled in said overhead rail, flyers suspended from said spindles, two rows of bobbin-carrying spindles normally aligned with said driven spindles, a bobbin-driving shaft extending intermediate 75 the rows of bobbin-carrying spindles, and a bobbin lifter rail supporting said bobbin-carrying spindles, and adapted to be tilted about the axis of said bobbin-driving shaft.

2. A roving frame as claimed in claim 1 80 in which the bobbin lifter rail is movable axially of the bobbin-driving shaft.

3. A roving frame as claimed in claim 1 having means for imparting tilting movement to the bobbin lifter rail, said means comprising a manually operable worm 85 meshing with a toothed segment attached to the bobbin lifter rail.

In testimony whereof we have signed our names to this specification.

GORDON FRASER.
NORMAN FRASER.
JOHN FRASER.
